UNITED STATES PATENT OFFICE.

THOMAS HERBERT JOHNSON, OF GLOUCESTER, NEW JERSEY.

DESIGN FOR A REVOLUBLE OR ROTATABLE TARGET.

53,914.

Specification for Design.

Patented Oct. 7, 1919.

Application filed December 15, 1916. Serial No. 137,276. Term of patent 14 years.

To all whom it may concern:

Be it known that I, THOMAS HERBERT JOHNSON, a citizen of the United States, residing at Gloucester, New Jersey, have invented a new, original, and ornamental Design for Revoluble or Rotatable Targets, of which the following is a specification, reference being had to the accompanying drawings, forming part thereof.

Figure 1 is a top or end view.
Fig. 2 is a side view showing my new design.

I claim:

The ornamental design for a revoluble or rotatable target, substantially as shown.

THOMAS HERBERT JOHNSON.
